UNITED STATES PATENT OFFICE.

ROBERT HENRY, OF PUEBLO, COLORADO.

ORCHARD-HEATING DEVICE.

No. 922,478.

Specification of Letters Patent. Patented May 25, 1908.

Application filed October 13, 1908. Serial No. 457,511.

To all whom it may concern:

Be it known that I, ROBERT HENRY, a citizen of the United States, residing at Pueblo, in the county of Pueblo and State of Colorado, have invented a certain new and useful Improvement in Orchard-Heating Devices.

My invention relates to devices for heating the air in orchards and protecting buds and fruit from injury at times of unusual cold; and the objects of my invention are; first, to provide a light, portable, heating device that may be swung from the limbs of a tree; second, to provide a heating device with draft adjustments usable among fruit trees and in orchards; and third, to provide such a device so that the same may be readily detached and stored in small space. I attain these objects by the mechanisms illustrated in the accompanying drawings, in which—

Figure 1 is a perspective view of my heating device with the top removed; Fig. 2 shows the base and legs upon which the device stands; Fig. 3 shows the top; Fig. 4 shows the lower damper; Fig. 5 shows the device in use; Fig. 6 shows the body or barrel of stove detached; and Fig. 7 shows in perspective view in broken sections the assembling of the different parts of said construction in operative relation.

Similar numerals refer to similar parts throughout the several views.

The barrel of the stove 1 is of sheet metal made in cylindrical form and attached by tongue and slot means 2 and 2^b. The base 3 is metal, preferably sheet metal, on which is constructed flaring legs 5 and upward extending elements 4. In base 3 are made open spaces 9 which are usable both as grate and draft means. The grate damper 6 is of slightly smaller diameter than base 3 and is constructed with extending arms one of which fits into slot 2^a and the other arm fits into a similar slot in the opposite side of 1. The grate damper 6 is also provided with slots 7 which exactly correspond to slots 9 and the spaces between 7 are as wide as the slots 9 in base 3. The grate damper being placed on top of base 3 it may be adjusted so as to control draft through 9 or to close the same completely. The tongues 2 on the barrel 1 are made as indicated extending backward from the near end of piece and exactly fitting into the slots 2^a, and being joined by these means the barrel is placed on the base 3 and by bolt means is attached to the upward

extending elements 4. Bail 12^b is provided. The top damper 11 is provided with exterior portion and with spaces to be controlled by wings 12^a turnable at the center 12. On the underneath side this top damper is also provided with perpendicular rim 12^c that exactly fits in the top of the barrel 1 thus holding the top of the contrivance outwardly so as to keep the tongue and slot 2—2^b engaged. By means of this damper the draft may be controlled in conjunction with grate damper as heretofore described.

The whole makes a structure light and adjustable that may be placed in an orchard of fruit trees in any desired numbers for use in warding off the effects of frosts either by producing heat or by means of what is known among orchardists as smudging or smoke which is produced to ward off the effects of frosts on fruit buds or fruit.

Owing to the simplicity of the structure the draft is perfectly controlled, and the device may be arranged with any combustible material either started and ready for burning or for use upon ignition, and the device if desired may be swung by wire underneath the limbs and among the foliage of the trees as shown in Fig. 5.

It has been found by horticulturists in making any successful protection against frosts or cold a wide distribution of heat is desired and as much as possible a direct application of the heated air through and underneath the foliage of the fruit trees thus requiring in all such heating devices an application of a considerable number to any area. Therefore in my device I have met one of the chief objections and have provided the means of readily adjusting the parts. When open the barrel spreads out as shown in Fig. 6 and any number may be stacked or crated together, and in like manner the bases, grate and top damper stack together, thus furnishing economy of space in shipment or storage, as all that is required is simply to remove the top damper and unscrew the bolts in elements 4 and slip out the tongues 2 from engagement in slot 2^b in order to detach and knock down the device after being set up.

I claim:

1. In an orchard heater of the character described, the combination of a cylinder, a base formed with flaring legs and with slots, said base being detachably connected to said cylinder and constituting an outer grate, and an inner grate formed with corresponding

22
slots and slidable upon said outer grate, the slots of the inner grate arranged to be carried into and out of alinement with those of the outer grate, all substantially as described.

5 2. In an orchard heater of the character described, the combination of a cylinder, a base formed with flaring legs and constituting an outer grate having slots therein, a cover provided with draft regulating means, 10 and an inner grate formed with correspond-

ing slots and slidable upon said outer grate, the slots of the inner grate arranged to be carried into and out of alinement with those of the outer grate, all substantially as described.

ROBERT HENRY
